RINALDO DEL PORTO, OF VALLEJO, CALIFORNIA.

DRILL EXTENSION.

1,376,139.

Specification of Letters Patent. Patented Apr. 26, 1921.

Application filed November 4, 1919. Serial No. 335,694.

To all whom it may concern:

Be it known that I, RINALDO DEL PORTO, a subject of the King of Italy, residing at Vallejo, in the county of Solano and State 5 of California, have invented new and useful Improvements in Drill Extensions, of which the following is a specification.

This invention relates to a drill extension and especially to an extension of the telescoping type.

One of the objects of the present invention is to provide a simple, substantial and easily operated telescopic extension adapted for communicating rotary motion from a driven 15 part or motor, engageable with one end of the extension, to a drill or other suitable tool attached to the opposite end of the extension.

Another object of the invention is to provide means for adjustably connecting the telescoping sections of the extension in such a manner that the distance between the driving motor and the drill may be varied to a considerable extent. Another object of the 25 invention is to provide a structure which permits the telescoping sections to be extended or retracted without breaking or otherwise interfering with the driving connection formed between the same. Another 30 object of the invention is to provide means whereby the rotary movement of the rotor or other driving member employed may be transmitted to extend or retract the telescoping members supporting the drill. Further 35 objects will hereinafter appear.

The invention consists of the parts and the construction, combination and arrangement of parts as hereinafter more fully described and claimed, having reference to 40 the accompanying drawings, in which—

Figure 1 is an exterior view of the drill extension.

Fig. 2 is a central, vertical section, partly in elevation and partly broken away.

Fig. 3 is a central, vertical section.

Fig. 4 is an enlarged cross section on line 4—4 of Fig. 2.

Fig. 5 is an enlarged detail section, showing the driving connection between the 50 driving tube and the screw rod.

Fig. 6 is a cross section on line 6—6 of Fig. 5.

Fig. 7 is an enlarged detail section of the lower end of the screw rod.

Fig. 8 is a cross section on line 8—8 of Fig. 7.

Referring to the drawings in detail, A indicates a tapered shank of suitable construction, which is adapted to be inserted in a chuck carried by a motor or other suitable driving member. Secured to the head of the shank, as shown at 2, is an inner driving tube 3 and an exterior covering tube 4. Formed on the lower end of the driving tube is an annular recess 5 and extending approximately from end to end of the driving tube are a pair of oppositely positioned slots 6. Rotatably mounted on the lower end of the driving tube is a nut 7 which is attached to the driving tube by means of a sleeve-like extension 8 and a snap ring 9. The upper end of the sleeve extension 8 is provided with an annular groove 10, into which the snap ring 9 is adapted to expand. The sleeve and the nut carried thereby are thus rotatably mounted on the end of the driving tube but they are secured against endwise movement by means of the snap ring specified.

Loosely fitting the interior of the driving tube and adapted to be extended or retracted with relation thereto is a screw rod 11, on the lower end of which is formed a chuck 12 for the reception of a drill 13 or similar tool. The drill rod is provided with square threads on the exterior surface, which engage the threads of the nut 7. The drill rod is otherwise provided with a central passage 14 and its upper end is slotted, as at 15, for the reception of a key or driving lug 16. The driving lug is sufficiently long to project into the opposite slots 6 formed in the driving tube 3 and a positive driving connection is thus formed between the driving tube and the screw rod 11. Attached to the key or driving lug 16 is a rod 17. This rod extends downwardly through the central passage 14 and its lower end is rotatably secured in a cross bar 18 which is slidably mounted in a slot 19 formed just above the chuck 12. A spring 20 is interposed between the cross bar 18 and the upper end 20' of the axial recess in which the spring is seated, the function of the spring being that of retaining the cross bar 18 in the depressed position shown and similarly the driving key or lug 16 in engagement with the slot 15 formed in the upper end of the screw rod. The lug or key 16 performs two functions; first, that of forming a positive driving connection between the screw rod and the driving tool; and secondly, that of

breaking the driving connection between the same when the screw rod is to be retracted, as will hereinafter be described.

The operation of the drill extension will be as follows: With the shank A secured in the chuck of a motor or other suitable driving member, it should be obvious that rotary movement will be transmitted through the driving tube to the screw rod and from the 10 rod through the chuck 12 to the drill or other tool supported.

With the screw rod completely retracted, as shown in Fig. 1, if it is desired to extend the same, it will only be necessary for the 15 operator to grasp the sleeve 8 carrying the nut 7. Securing the nut against rotary movement will cause the screw rod 11 to be extended. This is due to the fact that the screw rod is slidably mounted within the 20 driving tube but turns in unison with the same, due to the driving connection formed by the key 16, which projects into the slots 6. Rotation of the driving tube and the screw rod with relation to the nut, when this is 25 held stationary as described, will therefore cause a projection of the screw rod while a release of the nut 8 or the sleeve carrying the same will prevent further extension or elongation of the rod with relation to the 30 driving tube.

From the foregoing it can be seen that it is possible to quickly extend the screw rod 11 with relation to the driving tube when it is in operation as it is only necessary to 35 grasp the sleeve 8 and hold it stationary until the drill or the screw rod supporting the same has been extended as far as required. If it is desired to retract the drill and the screw rod supporting the same, or to telescope it with relation to the driving tube, it 40 is only necessary to grasp the chuck 12 and pull the cross rod 18 in an upward direction. This should be done when the drill is stationary. Pulling of the cross rod in an 45 upward direction will transmit a similar movement through the rod 17 to lift the key 16 out of the slot in the upper end of the screw rod. The driving connection between the screw rod and the driving tube is 50 thus broken and the screw rod may therefore be held stationary. Rotary movement is then transmitted to the driving tube, and as the screw rod is held stationary, it should be obvious that it will be retracted, due to 55 the fact that it is held stationary while the other parts are revolving. In this connection it will be observed that the snap ring 9 produces the required friction to form a driving connection between the tubes 3 and 60 4 and the nut 8, when the screw rod is retracted. The cross rod is released the moment the screw rod has been sufficiently retracted and the driving connection between the tube 3 and the screw rod will immediately be formed as the spring 19 will depress 65

the connecting parts, or in other words, draw the key 16 downwardly, thus forming the driving connection previously specified.

The extension here shown may be extended by the rotary power of the driving member and it may similarly be retracted. It is substantial and simple in construction and may be amply lubricated as all the parts employed, with the exception of the sleeve and nut, are inclosed by means of the exterior 75 covering tube 4. Chance of waste, chips or dirt entering through the slots 6 is furthermore obviated.

The extension may also be retracted or extended by merely grasping the tube 4 and 80 turning the sleeve and nut by hand in either direction but it should be obvious that power extension and retraction is preferable as it can certainly be more quickly accomplished.

While several features of the present invention are more or less specific in construction, I wish it understood that various changes may be resorted to within the scope of the appended claims; similarly, that the materials and finish of the several parts employed may be such as the experience and judgment of the manufacturer may dictate.

Having thus described my invention, what I claim and desire to secure by Letters Patent is—

1. A drill extension comprising a pair of telescopic members, one of which is threaded, means frictionally connected to the other for engaging with the threads of the first member, means for coupling the members 100 together, and means extending through the inner member for rendering the coupling means inoperative.

2. A drill extension comprising a pair of telescopic members, one of which is threaded, means frictionally connected to the other for engaging with the threads of the first member, a coupling member arranged within the outer telescopic member for coupling the two telescopic members together and an uncoupling member extending axially through the inner telescopic member and operable to render said coupling member inoperative.

3. A drill extension comprising a pair of telescopic members, one of which is threaded, means frictionally connected to the other for engaging with the threads of the first member, the outer member formed with a lengthwise slot, the inner member formed with an axial bore and in its inner end with a slot registerable with the slot of said outer member, a key member movable into the registering slots to couple the telescopic members together, and means operable through the axial bore to disengage the key from one of the slots of said members.

4. A drill extension comprising a pair of telescopic members, one of which is threaded, means frictionally connected to the other for 130

engaging with the threads of the first member, the outer member formed with a lengthwise slot, the inner member formed with an axial bore and in its inner end with a slot 5 registrable with the slot of said outer member, a key member movable into the registering slots to couple the telescopic members together, a rod slidable in the axial bore and carrying the key member on its inner end, 10 and an actuating member rotatably connected to the opposite end of the rod and operable from the exterior of the telescopic member to slide the rod.

5. A drill extension comprising a driving 15 shank, a driving tube secured thereto, a screw rod interior of the driving tube and adapted to telescope with relation thereto, a pair of aligned slots formed in the driving tube and extending approximately from end 20 to end thereof, and a key member on the screw rod within the tube for extending into said slots to form a driving connection between the tube and the screw rod.

6. A drill extension comprising a driving 25 shank, a driving tube secured thereto, a screw rod interior of the driving tube and adapted to telescope with relation thereto, a pair of aligned slots formed in the driving tube and extending approximately from end 30 to end thereof, a key member on the screw rod extending into said slots to form a driving connection between the tube and the screw rod, and a nut rotatably mounted on the driving tube and engageable with the 35 threads on the screw rod, said nut rotatable with the tube when the key is disconnected from the screw for retracting the latter within said tube.

7. A drill extension comprising a driving 40 shank, a driving tube secured thereto, a screw rod interior of the driving tube and adapted to telescope with relation thereto, a pair of aligned slots formed in the driving tube and extending approximately from end 45 to end thereof, a key member within the tube and on the screw rod extending into said slots to form a driving connection between the tube and the screw rod, a nut rotatably

mounted on the driving tube and engageable with the threads on the screw rod, means exterior of and below the tube for disengaging the key member from the screw, and a tool-supporting chuck on the lower end of the screw rod.

8. A drill extension comprising a driving 55 shank, a driving tube secured thereto, a screw rod telescopic within the driving tube and having screw threaded engagement therewith, a pair of aligned slots formed in the driving tube and extending approximately 60 from end to end thereof, a key member slidably mounted in the screw rod and projecting into the slots in the driving tube to form a driving connection between the driving tube and the screw rod, and means 65 for moving the key into and out of engagement with relation to the screw rod.

9. A drill extension comprising a driving shank, a driving tube secured thereto, a screw rod within the driving tube and 70 adapted to telescope with relation thereto, a pair of aligned slots formed in the driving tube and extending approximately from end 75 to end thereof, a key member slidably mounted in the screw rod and projecting into the slots in the driving tube to form a driving connection between the driving tube and the screw rod, means for moving the key into and out of engagement with relation to the screw rod, a nut supported by 80 and rotatably mounted on the lower end of the driving tube and frictionally related thereto for rotating therewith, the threads of said nut engaging the threads of the screw rod, a cover tube exterior of the driving tube and secured thereto, and a tool-supporting chuck on the lower end of the screw 85 rod.

In testimony whereof I have hereunto set my hand in the presence of two subscribing 90 witnesses.

RINALDO DEL PORTO.
